COMPOSITE PISTON

Application filed February 15, 1929. Serial No. 340,067.

The invention relates to pistons and more especially to that class of pistons wherein the head and skirt are composed of different materials, such pistons being commonly termed 5 "composite pistons".

The object of the invention is to provide such composite piston which is particularly adapted for use in internal combustion engines and which, moreover, though of great 10 strength and rigidity, will be of minimum weight and operate at low temperature and will not be subject to overheating.

A further object of the invention resides in the provision of a piston structure of this 15 type such that the piston as a whole will retain its shape under the various conditions of temperature and physical loading to which it is subjected in operation and in which no internal unsymmetrical stresses will 20 develop as a result thereof.

A still further object of the invention is to design the members composing said piston of shapes to allow of ready and cheap manufacture and assembly thereof into a 25 complete piston.

Heretofore, it has been the practice to form composite pistons by bolting, riveting or casting together a skirt portion, as of cast iron or steel, to a head portion of 30 aluminum alloy or other light metal of high thermal conductivity. However, failure has usually resulted at the joint between the two metals due to the wide difference in their 35 respective rates of expansion; and the high stresses produced in the structure under changes of temperature have also produced distortions in these pistons which are particularly objectionable in designs of piston whose parts are not diametrically symmetri- 40 cal, or wherein casting strains occur during the process of fabrication.

In the novel piston forming the subject matter of the present invention, these objectionable features are eliminated; and a 45 novel manner of forming joints between the metal parts having different coefficients of expansion provides for the various parts to retain their proper shape irrespective of the temperature changes involved.

50 This is attained by providing a skirt, as

of sheet metal, with an inturned flange at its extreme outer end, which flange jointly supports an annular ring-groove member within which is frictionally held a head of material different from that composing the 55 ring member, for example, aluminum, and the diameter of which head normally exceeds the diameter of said ring-groove member to an extent such that adequate holding 60 friction will prevail between the two members at the lowest operating temperature and such that, furthermore, no pressures are developed at the highest operating temperature which will exceed the yield points of 65 the two materials. The arrangement thereby is such that the softer metal will not be in contact with wearing surfaces and the piston will thus have maximum operating life.

The nature of the invention, however, will best be understood when described in connection with the accompanying drawings, in which:

Fig. 1 is a longitudinal section through the novel composite piston. 75

Fig. 2 is a transverse vertical section taken on the line 2—2, Fig. 1 of the drawings with the piston head removed and before the grooves are cut in the ring therefor.

Fig. 3 is a horizontal section taken on the line 3—3, Fig. 1 of the drawings. 80

Figs. 4 and 5 are vertical sections of different types of heads, the taper shown in Fig. 5 being on a greatly exaggerated scale.

Fig. 6 is a perspective view of an integral 85 wrist pin boss and supporting bridge therefor.

Fig. 7 is a vertical section through a skirt member with modified form of wrist pin support; and Fig. 8 is a vertical section thereof taken on the line 8—8, Fig. 7. 90

Referring to the drawings, 10 designates the skirt member of the piston which is preferably formed as a sheet steel-drawn cup and is characterized by a deep inturned flange 11 95 at its extreme outer or head end. Diametrically disposed openings 12 and 13, moreover, are formed in the skirt member, the same having the lips 14 and 15 to accommodate wrist pin bosses 16 and 17 respectively. The 100

inner ends of these bosses are supported by, or preferably formed integrally with, triangular shaped bridges 18, the outer faces of which are arranged to contact with the inner 5 face of the flange 11 and are rigidly attached to said flange as by spot welding, brazing or soldering the same thereto. These bridge members are arranged parallel to each other, as shown, preferably in chords of the cylindrical skirt member. The inner end of the 10 skirt member may, also, be provided with the inturned flange 19 to stiffen the same at this point, as well as to provide a pilot for subsequent machining operations.

15 The wrist pin bosses may be formed, also, with independent screw bosses 20 as indicated in Figs. 7 and 8, or they may be constructed integrally with the corresponding bridges as hereinbefore described; and this 20 latter construction is especially desirable in designs wherein a wrist pin turns in its wrist pins boss, in which case, they are designed to receive bushings 21.

Carried by the said flange 11 and rigidly 25 secured thereto, as by welding, is a thick-walled steel head ring or annular ring-groove member 25 provided with piston ring grooves 26 and cylindrically bored through; and the same is designed to retain the head 27 of the 30 piston. This is in the nature of a symmetrically-formed block of aluminum alloy, or other light metal, and its outer diameter is normally larger than the inside diameter of the ring 25, being pressed or shrunk in place 35 therein so that its inner face 28 is in contact with or seats upon the outer face of the flange 11.

The minimum amount by which the diameter of said head 27 exceeds the diameter of 40 the bore of ring 25 is such as to produce adequate holding friction at the lowest temperature of operation and that no pressures are developed at the highest operating temperatures which will exceed the yielding points of 45 the two materials; and the amount of which excess will, of course, be determined by the nature of the alloy employed.

As the temperature of the assembled piston head rises in operation, the portion 27 50 will tend to expand more than its surrounding steel ring member 25 and thus pressure between the contacting surface is increased. The operation temperature of head 27 at its inner end, however, will be lower than at its 55 outer end, which is exposed to the highest temperature, because of heat dissipation through the successive piston rings (not shown) and retained by the grooves 26. To secure a more even distribution of the pressure (temperature) throughout the length of 60 a joint as well as to maintain high total wall friction at the said joint without the development of excessive pressure at the hotter end of the head 27, said head may be of taper 65 form, being of greater diameter at its inner

end, as indicated in Fig. 5, and assembled in an annular ring-groove member having a straight cylindrical bore, as in the case of the member 25. Moreover, the joint between the head 27 and its holding ring member 25 results in minimum restriction to the flow of heat; and because of the intimate contact and the pressure exerted between these interfitting parts, it offers less total restriction than the loose contact surfaces of piston rings and their grooves whereby a large part of the heat entering the head is dissipated to the cooler cylinder wall in which the piston operates.

In operation, the loads are transmitted to the wrist pin bosses at their outer ends through the wall of the skirt member and at their inner ends through the bridges 18 as a result of the contact with the flange 11. This arrangement constitutes stiff straight-line 85 compression and strong tension members so that loads due to the gas pressure within the cylinder in which the piston operates, or due to inertia, will not tend to distort the structure nor change the roundness of the skirt member, nor will it cause misalignment of the wrist pin boss center lines. This allows of making pistons of sections of minimum thickness and with consequent decrease in 90 weight of such pistons.

Also, changes in temperature in operation do not cause distortion or change in the roundness of the head 27 and the peripheral ring lands 26 in the surrounding ring-groove member 25 which are symmetrical and tend to expand with a uniform increase in diameter. Actually, the shape of the head in conjunction with the flange 11 effects control of the shape or roundness of the head end of the piston assembly, which portion is that subjected to the greatest temperature changes. Furthermore, due to the fact that the bridges 18 are attached to the stiff control flange 11, or to the skirt wall only adjacent thereto, which may be effected at the portions 28 and at a point above the center lines of said bosses, they have no restrictive effect upon the natural diametrical expansion or contraction of the skirt wall due to changes in temperature of this part.

Moreover, the said bridges 18 are comparatively weak in a direction to restrict movement of the skirt in a radial direction, whereby the said skirt is substantially free to expand or contract and tends to do so symmetrically so that it may be closely fitted to a surrounding cylinder. The inertia load tending to force the head 27 outwardly from its surrounding ring-groove member 25 is adequately restricted by the frictional resistance offered as a result of the fit between the two parts, as aforesaid; and with respect to any tendency of the same to be forced inwardly into the skirt, the flange 11 upon 115

which it seats provides an adequate abutment.

The design of the novel piston provides for a minimum quantity of the higher cost aluminum alloy which is utilized therein only where its heat-conducting property is most useful while the remaining portions of the piston may be constructed of materials requiring greater strength and resistance to wear and which are also less expensive. Furthermore, all of the component parts of the piston lend themselves to rapid and inexpensive manufacture; but it is understood that while the preferred materials only have been set forth, other materials may be utilized and the form of the design changed without departing from the scope of the invention.

It is to be noted, also, that in composite pistons made according to the construction hereinbefore set forth and within the limits of fits stated, the joints between the two metals composing the head of said piston are entirely permanent and looseness will not develop as a result of the many changes of temperature involved in the operation of these pistons. This feature is a particular improvement upon the type of joints heretofore proposed in composite pistons, which gradually loosen and break down due to the failure of mechanical fastening, to the developing of stresses above the yield points of the materials, to limitation of the particular alloy employed, to the heat treatment of, and the fits possible when aluminum alloys are cast into or around the harder metal.

I claim:

1. A composite piston comprising a skirt of sheet metal having an inturned flange at its outer end and provided with openings in the wall, wrist pin supporting means within said skirt embodying tubular members fitting the respective openings and depending bridge elements carrying the same and attached to the said flange, an annular ring-groove member secured to said flange, and a head of material different from that comprising the ring-groove member, solely held frictionally thereby against outward movement relative thereto and seating on said flange.

2. A composite piston comprising a skirt member having an inturned flange at its outer end, an annular ring-groove member attached to said flange, and a head of material different from that comprising the ring-groove member, solely held frictionally thereby against outward movement relatively thereto and seated on said flange.

3. A composite piston comprising a skirt member having an inturned flange at its outer end, an annular ring-groove member attached to said flange, and a head of material different from that comprising the ring-groove member, solely held frictionally thereby against outward movement relatively thereto and seated on said flange, the diameter of said

head with respect to the diameter of said annular ring-groove member being such that adequate holding friction prevails between the two members at the lowest operating temperature and no pressures are developed at the highest operating temperature exceeding the yield points of the two materials.

4. A composite piston comprising a skirt member having an inturned flange at its outer end, a ring-groove member having a cylindrical bore and attached to said flange, and a head when cold being in the form of a truncated cone and of material different from the annular ring-groove member and solely held frictionally thereby against outward movement relatively thereto.

5. A composite piston comprising an annular ring-groove member, a head of material different from that composing the ring-groove member and solely held frictionally thereby against outward movement relatively thereto, and a skirt member having an inturned flange at its extreme outer end jointly supporting the said ring-groove member and the said head.

6. In a piston, an upright tubular skirt provided at its upper end with an inturned skirt flange and provided at some distance below the said flange with diametrically opposed and coaxial apertures, and two journal supports spaced along the axis of the said perforation; each journal support comprising an upright plate extending at right angles to the said axis, a tubular portion integral with the plate and socketed in one of the said apertures, and two horizontal plate flanges underhanging and secured to spaced portions of the skirt flange, the said tubular portion and the two plate flanges extending respectively in opposite directions from the upright plate supported at both ends by the said flange.

7. In a piston, an upright tubular skirt provided at its upper end with an inturned skirt flange and provided at some distance below the said flange with diametrically opposed and coaxial apertures, and two journal supports spaced along the axis of the said perforation; each journal support comprising an upright plate extending at right angles to the said axis and a tubular portion integral with the plate and socketed in one of the said apertures, each plate having at each end of its upper portion two plate flanges respectively secured to the said skirt flange and to a portion of the skirt adjacent to the skirt flange.

8. In a piston, a tubular skirt provided at its upper end with an inturned radial skirt flange and also provided with diametrically opposed tubular journaling formations formed from the skirt, the journaling formations having a common axis intersecting the axis of the skirt; two journaling tubes each shorter than one-half the bore of the skirt and each having its outer end socketed in one

of the journaling formations; and two tube supports each fast upon the inner end of one of the tubes; each tube support comprising an upright and flat plate chordate to the skirt and provided at its entire periphery with a plate flange extending transversely of the said plate, the plate flange including two upper portions respectively underhanging and secured to two circumferentially spaced parts of the skirt flange, the plate flanges and the tubes having the same temperature coefficients of expansion as the skirt, and the plate flange including upper and lower medial portions bowed to extend relatively near to the inner end of the tube.

15 In testimony whereof I affix my signature.
WINTHROP S. HORTON.
